UNITED STATES PATENT OFFICE

ALBERT WILLIAM ROGERS, OF SANCHEZ, DOMINICAN REPUBLIC

RAILWAY TRACK

Application filed June 30, 1927, Serial No. 202,624, and in Great Britain February 11, 1927.

This invention, which relates to railway tracks, consists in the provision of a track which includes rails of a more or less T-headed shape with wedge-like web, rail jointing with wedge-like sleeves or compound fish-plates and special keys for use therewith, rail chairs of a more or less horseshoe shape in cross-section, with special keys for use therein, and sleepers 5 wherein no bolts, spikes or screws are employed to make the fastening between rail ends, and between rails and chairs, or between chairs and sleepers when concrete sleepers are employed, and in which sleepers, which are reinforced, the aforesaid chairs are embedded.

In order that the said invention may be the more readily understood, reference is to be had to the following description and 20 accompanying sheets of drawings, wherein:

Figure 1 is a view, partly in elevation and partly in section, illustrative of a concrete sleeper, showing also rails and rail chairs.

Figure 2 is a plan view, partly in section, of said sleeper.

Figure 3 is a longitudinal elevational view illustrative of the joint of two rails, and one of said rails secured in a chair of a 30 joint sleeper.

Figure 4 is a sectional view, taken on line 4—4 of Figure 3.

Figure 5 is a sectional view, taken on line 5—5 of said Figure 3.

Figure 6 is an underside plan view illustrative of one of the jointing keys.

Figure 7 is a perspective view of one of the chair keys.

Like numerals of reference indicate corresponding parts in the several figures.

In carrying out the invention and referring to the drawings, the rails, instead of being of the present-day standard rail section, are now made, as shown in Figures 45 1, 3, 4 and 5, with a more or less T-shaped head 1, and formed with a web 2, i. e. the tail of the T is of wedge-shape, the thin end of the web 2 joining the head 1, which, on its underside, is formed with longitudinal and semi-circular grooves 3 extending

the length of the rail and disposed one each side of the thin end of the web 2 aforesaid.

Each sleeper 4, of convenient length, width and thickness, is made of concrete reinforced by means of longitudinally disposed hook-ended round metal bars 5 to withstand the pressure which is applied in a lateral direction by the keys and rail chairs 6, which latter are embedded in 55 gauged distance apart in the concrete sleeper 4, said sleeper 4 being on its underside formed with flat ends or bearing surfaces 7 connected together by a central and upwardly curved portion 8.

Each rail chair 6 comprises a cast-steel member, of a length equal to the width of the sleeper 4, and of a more or less horseshoe shape in cross-section, embedded in the sleeper 4, and with the heel ends 9 of its walls flush with the upper surface of the 60 sleeper 4, said chair 6 being formed with oppositely disposed exterior ribs 10 to anchor said chair in the concrete.

To place and secure a rail in a chair 6 of a concrete joint sleeper 4, a wooden or iron packing piece may be placed in the bottom 75 of the chairs of the joint sleepers, the thickness of said packing pieces being such as to raise the rail when placed thereon to the required level to enable the keys to be placed 80 and driven in into the chairs of the intermediate sleepers, whereupon the packing pieces are removed and the keys inserted in the chairs of the joint sleepers.

These keys, respectively 11 and 12, are 85 cast-steel keys of a shape in cross-section (see Figure 5) to suit the space bounded by the inner wall of the chair 6 and that face of the wedge-shaped web 2 of the rail opposite said wall, and of said keys 11 and 12, 90 which are on their upper part each provided with a longitudinal and semi-cylindrical bead 13 which extends the length of the key. The key 11 for placement on the inside of the rail is uniform in section, whilst the key 12 for placement on the outside of the rail is tapered, the inside key 11 being simply placed in position, whilst the outside key 12 is driven into position, the semi-circular heads 13 of said keys 11 and 12 taking in 95 100

the semi-circular grooves 3 in the underside of the head 1 of the rail, and in this way is said rail suspended by the two keys 11 and 12 aforesaid, with the end of the wedge-shaped web 2 clear of the bottom of the 5 chair 6 aforesaid.

Further, the inside key 11 is formed with a vertically disposed triangular groove 14 (see Figure 5), to coincide, after adjusting 10 said key 11, with a vertically disposed triangular groove 15 in the adjacent wall of the chair 6, and into the square hole thus formed there is fitted a slightly tapered squared plug 16 which locks said key 11 to 15 said wall, whilst the outside key 12 is formed with four vertically disposed triangular grooves 17 (see Figure 7) arranged parallel to one another, and the wall adjacent said key 12 is formed with five vertically 20 disposed triangular grooves 18, only one of which is shown in Figure 5, arranged parallel to one another to form, when a groove 17 in the key 12 aligns with a groove 18 in the wall, a square hole in which is 25 fitted a slightly tapered squared plug 19.

For each rail joint (see Figures 3 and 4), there is employed a compound fish-plate, the same comprising a cast-steel sleeve of convenient length and of wedge-shape trough-like cross-section, that is to say, the longitudinal walls 20 of the sleeve incline upwardly and inwardly to one another to receive therebetween the wedge-shaped web 2 of the rail.

In the upper face of each wall 20 of the 35 sleeve, and towards one end thereof, and which walls taper longitudinally in opposite directions in relation to one another, are formed a convenient number of transversely disposed triangular grooves 21 (Figure 3) 40 arranged parallel to one another.

Further, two tapered keys 22 are provided, said keys on their upper face each being formed with a longitudinally disposed semi-cylindrical bead 23 which extends the length 45 of the key 22, and on their lower surfaces with a convenient number of transversely disposed triangular grooves 24 arranged parallel to one another.

The jointing-up is effected in the following 50 way. The sleeve is slipped over the end of a rail which, it is assumed, is in position. The second rail is then placed in position and secured to its sleepers in the manner previously described, and the sleeve is moved to 55 enable the keys 22 to be inserted under the rail head 1 and on top of the walls 20 of said sleeve, the beads 23 of said keys 22 taking in the grooves 3 in the underside of the head 1 of the rail. The sleeve aforesaid is then adjusted to engage both rail ends (as shown in 60 Figure 3), whereupon the keys 22 are firmly driven in to complete the joint, forcing the sleeve downwards so that the walls 20 of said sleeve tightly wedge with the wedge-shaped 65 webs 2 of the rails.

The keys are each locked in position by means of a slightly tapered squared plug 24 which fits in one of the squared holes formed by one of the triangular grooves 24 in said key 22 and one of the triangular grooves 21 in the 70 walls 20 of the sleeve according to the aligning position of said triangular grooves.

The triangular grooves in each wall of the sleeve are five in number and half-inch from point to point, giving a total length of two-and-a-half inches, whilst the triangular grooves in each key are four in number, and measure half-inch also in width, but are spaced apart one-eighth-inch, which distance the keys must be moved to enable the plug to 80 be inserted into the next square hole presented, the intervening points formed by the triangular grooves being removed to give a suitable clearance.

The keys 22 are intended to occupy the position in which the second groove 21 in a wall 20 of the sleeve aligns with the first groove 24 in a key 22 when first driven, when, for practical purposes and wear and tear, an adjustment of seven-eighths inch, or seven positions 90 of the plug, is provided for by the remaining grooves.

In all cases the plugs are dipped in tar before being placed in position, after which they are inserted and tapped sufficiently to ensure a 95 firm hold on the sides of the hole, the unoccupied grooves in the tapered keys being filled in with grease.

Further, the tapered joint keys may be made concave at the thick end to facilitate 100 their being drifted into position, instead of being driven, in the event of close joint sleeper spacing being required.

Although the primary object of the invention is to eliminate bolts, spikes and screws 105 whilst making for extensive use of concrete sleepers, yet the rail section above described and the boltless rail joint can be used to advantage in combination with wooden sleepers and chairs modified to suit said wooden 110 sleepers.

I claim:—

1. A device of the character described including a sleeve having a base and upwardly extending spaced side walls, a T-shape rail adapted to be supported in said sleeve, fish plates interposed between said sleeve and rail, said plates and sleeve being formed with co-operating locking grooves, and studs insertable in said grooves for holding said fish plates and rail in adjusted position in said sleeve.

2. A device of the character described including a sleeve having a base and upwardly extending spaced side walls, a T-shape rail having a wedge-shape web adapted to be supported in said sleeve, adjustable fish plates adapted to have contact with said sleeve and the web and head portions of said rail, the adjacent portions of said sleeve and fish plates 120

being provided with a plurality of spaced opposed cooperating locking grooves, and locking lugs receivable in said grooves for holding the fish plates and rail in said sleeve.

5 In testimony whereof I have affixed my signature hereto this 3rd day of May, 1927.

ALBERT WILLIAM ROGERS.
